UNITED STATES PATENT OFFICE.

GEORGE A. JOHNSON, OF CHICAGO, ILLINOIS, ASSIGNOR TO WILLIAM H. MINER, OF CHICAGO, ILLINOIS.

FRICTION-BUFFER FOR RAILWAY-CARS.

992,428.

Specification of Letters Patent. Patented May 16, 1911.

Application filed November 25, 1910. Serial No. 594,103.

To all whom it may concern:

Be it known that I, GEORGE A. JOHNSON, a citizen of the United States, residing in Chicago, in the county of Cook and State of Illinois, have invented a new and useful Improvement in Friction-Buffers for Railway-Cars, of which the following is a specification.

My invention relates to improvements in friction buffers for railway passenger cars.

The object of my invention is to provide a friction buffer suitable for use on railway passenger cars, which will be of a strong, simple, efficient and durable construction, which will be compact in form while providing for the necessary extended movement of the buffer bar, in which all the parts may be permanently connected together and adapted to be conveniently and quickly applied to or removed from the car.

My invention consists in the novel construction of parts and devices and in the novel combinations of parts and devices herein shown and described, and more particularly specified in the claims.

In the accompanying drawing forming a part of this specification, Figure 1 is a central, vertical section of a friction buffer embodying my invention, certain of the parts being shown in elevation. Fig. 2 is a cross section on line 2-2 of Fig. 1. Figs. 3, 4 and 5 are detail, vertical sections of the buffer mechanism, showing the same at Fig. 3 uncompressed, at Fig. 4 partially compressed, and at Fig. 5 compressed. Fig. 6 is a detail, cross section on line 6-6 of Fig. 3. Figs. 7 and 8 are detail cross sections on line 7-7 of Fig. 4, Fig. 7 looking in one direction and Fig. 8 in the opposite direction. Fig. 9 is an end elevation, looking from the line 9-9 of Fig. 5, and Fig. 10 is the opposite end elevation, looking from the line 10-10 of Fig. 5.

In the drawing, 1 represents a portion of the car frame, 2 the buffer cage or cradle secured to or forming part of the car frame, 3 the steel floor plate of the vestibule of the car, 4 the buffer plate carrying the movable floor plate 5, and 6 the buffer bar.

The buffer frame or cradle 2 has an upright transverse member 7, against which abuts the rear end of the friction shell or cylinder 8, which contains at its front portion the friction shoes 9, wedge 10 and interposed anti-friction rollers 11. At its rear

end, the buffer bar engages a buffer cap or block 12, which has a socket 13 to receive the rear end of the buffer bar, an annular chamber 14 to receive and support the front end of the main or primary buffer spring 15, which is interposed between the friction shoes 9 and said buffer cap 12.

The buffer cap 12 has an integral, central, hollow stud or thrust member 16, the inner end of which engages or abuts against the front end of the wedge 10 after the main or primary buffer spring 15 has been compressed, as shown in Fig. 4, the buffer mechanism as a whole being at this time only partially compressed. The buffer cap 12 also has an integral external stop member 17 adapted to abut against the front end 18 of the friction shell 8, and thus limit the inward movement of the buffer bar and prevent the springs from being compressed completely solid.

The supplemental of secondary buffer springs 19 and 20 are interposed between the friction shoes 9 and the friction shell 8, the spring 20 being a smaller spring fitting 80 and nesting within the larger spring 19. The secondary buffer springs 19, 20 are much stronger than the main or primary buffer spring 15, the capacity of the secondary buffer springs 19, 20 being preferably several times that of the primary buffer spring 15, so that when the latter is fully compressed, as shown in Fig. 4, the springs 19, 20 will only be slightly compressed, and the friction shoes 10 will have only made a small 90 portion of their total movement. This will be understood from Figs. 3, 4 and 5 of the drawing.

The friction shoes 9 are furnished with an internal flange or shoulder 21 for the outer end of the smaller spring 95 20 to bear against, the inner end of this spring bearing against a cap or seat member 22 with which the friction shell is provided at its rear end. The friction shell has at its rear end an inwardly projecting flange 23 100 to form a seat or shoulder for the inner end of the larger spring 19 to bear against. This flange 23 of the friction shell has an annular recess 24, to receive an external flange 25 on the cap 22.

All the parts of the buffer are connected together in assembled position and in compact form by means of a central connecting bolt or rod 26, having a threaded nut 27 at its rear end, fitting in the chamber of the 110

hollow cap 22, and which rod extends through the springs 19, 20, wedge 10 and into the hollow stud 16 of the front buffer cap or block 12. A stop thimble 28 is interposed between the wedge 10 and the head 29 of the connecting bolt or rod 26, and this stop thimble has an external flange or shoulder 30, which engages an internal flange or shoulder 31 on the hollow stud or thrust member 16 of the front cap or buffer block 12. When the parts are assembled, as shown in Fig. 3, the stop thimble 28, which is interposed between the head of the connecting bolt and the wedge 10, enables the secondary buffer springs 19, 20 to be put under an initial compression by the connecting bolt sufficient to take up and compensate for all wear of the friction cushioning mechanism. The connecting bolt also enables the main buffer spring 15 to be put under an initial compression when the parts are assembled. As the front buffer cap or block 12, the main and secondary buffer springs, the friction shell, friction shoes, wedge and rollers are all connected together in assembled position, as one piece, by the connecting bolt or rod 26, the buffer cushioning mechanism may be very quickly and conveniently applied to or removed from the car as occasion may require.

To hold the friction shell or cylinder 8 rigidly in place in the buffer frame or cradle 2, I provide the same with removable anchor straps or bands 32, having threaded ends 33, furnished with nuts 34 and cotters 35. The buffer frame or cradle 2 is further provided with a separate piece or removable bottom plate 36.

The primary spring is supported and centered at its front end by the central thrust member 16 of the front buffer cap 12, and at its rear end by the wedge 10 which has a circular or cylindrical extension 37 to enable it to perform this spring centering and supporting function.

I claim:

1. In a friction buffer, the combination with a buffer bar and front buffer cap, of a friction shell and friction shoes and wedge within the shell, a primary buffer spring reacting at one end against the front buffer cap and at its other end against said friction shoes, a secondary buffer spring reacting at one end against the friction shell and at its other end against the friction shoes, said front buffer cap acting through the wedge and friction shoes to compress the

secondary buffer spring after the main buffer spring has been compressed, substantially as specified. 60

2. In a friction buffer, the combination with a buffer bar and front buffer cap, of a friction shell and friction shoes and wedge within the shell, a primary buffer spring reacting at one end against the front buffer cap and at its other end against said friction shoes, a secondary buffer spring reacting at one end against the friction shell and at its other end against the friction shoes, said front buffer cap acting through the wedge 70 and friction shoes to compress the secondary buffer spring after the main buffer spring has been compressed, and a rod connecting the front buffer cap with the friction shell, substantially as specified. 75

3. In a friction buffer, the combination with a buffer bar and front buffer cap, of a friction shell and friction shoes and wedge within the shell, a primary buffer spring reacting at one end against the front buffer 80 cap and at its other end against said friction shoes, a secondary buffer spring reacting at one end against the friction shell and at its other end against the friction shoes, said front buffer cap acting through the wedge 85 and friction shoes to compress the secondary buffer spring after the main buffer spring has been compressed, and a rod connecting the front buffer cap with the friction shell, said connecting rod having a thimble at one 90 end engaging the wedge, substantially as specified.

4. In a friction buffer, the combination with a buffer bar and front buffer cap, of a friction shell and friction shoes and wedge 95 within the shell, a primary buffer spring reacting at one end against the front buffer cap and at its other end against said friction shoes, a secondary buffer spring reacting at one end against the friction shell and at its 100 other end against the friction shoes, said front buffer cap acting through the wedge and friction shoes to compress the secondary buffer spring after the main buffer spring has been compressed, and a rod connecting 105 the front buffer cap with the friction shell, said connecting rod having a thimble at one end engaging the wedge, said thimble having a flange at its front end engaging said front buffer cap, substantially as specified. 110

GEORGE A. JOHNSON.
